R. S. THOMPSON

BODY GARMENT OF THE CORSET OR GIRDLE TYPE

Filed August 2, 1924

Fig. 1.

Fig. 2.

Geo. P. Kimmel. ATTORNEY.

UNITED STATES PATENT OFFICE.

RALPH S. THOMPSON, OF NEW YORK, N. Y.

BODY GARMENT OF THE CORSET OR GIRDLE TYPE.

Application filed August 2, 1924. Serial No. 729,764.

To all whom it may concern:

Be it known that I, RALPH S. THOMPSON, a citizen of the United States, residing at New York city, in the county of New York and State of New York, have invented certain new and useful Improvements in Body Garments of the Corset or Girdle Type, of which the following is a specification.

This invention relates to a body garment of the corset or girdle type, and has for its object to so construct and arrange the garment to prevent the front thereof from riding up and buckling when the garment is worn and furthermore to provide snug fitting against the hips and thighs of the wearer.

A further object of the invention is to provide as a permanent part of the body of the garment automatically adjustable anchoring means to cause a permanent snug fit when worn, as well as to prevent the buckling and riding up of the garment irrespective of the attitude of and without any discomfiture to the wearer.

Further objects of the invention are to provide, in a manner as hereinafter set forth, a body garment of the corset or girdle type, which is simple in its construction and arrangement, strong, durable, including an elastic body portion, conveniently positioned, thoroughly efficient in its use, preventing pull or strain on the wearer irrespective of the attitude which the wearer assumes, and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is a front elevation of a body garment, in accordance with this invention.

Figure 2 is a like view of a modified form.

By way of example, a body garment in accordance with this invention, is illustrated as of the corset type, and with reference to

Figure 1, the body portion thereof which is of band-like form is indicated generally 55 by the reference character 1 and constructed of two sections referred to generally by the reference characters 2, 3.

Each of the sections comprises a substantially quadrangular impervious sheet of elastic material, indicated at 4, and preferably set up of pure rubber gum. The sections 2, 3 provide an elastic band-like body portion substantially of arcuate contour.

The sheet 4 has the upper and lower marginal portions thereof folded and inherently secured to the outer face of the sheet to provide reinforcing top and bottom edges 5, 6, respectively.

The lower portion of the inner side of each sheet 4 is incut to provide a diagonally disposed cut-out which gradually decreases in width inwardly. The cut-out of one sheet is oppositely disposed with respect to the cut-out of the other sheet, thereby providing 75 the lower part of the body of the garment, at the center thereof, when the sections are connected together, with a cut-away portion 7, semi-heart shaped in contour and opening at the bottom edge of the body portion 1. 80 The cut-away portion 7 extends laterally from each side of the vertical median, at the center of the front of the body portion 1.

The providing of the body portion 1 with the cut-away portion 7 forms a pair of oppositely extending triangular-shaped portions 8, 9. The portions 8, 9 project towards each other.

Each of the sheets 4, at its outer end, has secured thereto a laterally extending flexible 90 casing 10, provided with stays 11 and a row of eyelets 12. A lacing, not shown, is common to the eyelets 12 for adjustably securing the body portion 1 to the wearer. When the garment is worn, the casings 10 are arranged 95 against the back of the wearer.

Secured to the inner end of one of the sheets 4, is a laterally extending flexible casing 13, and secured to the inner end of the other sheet 4 is a laterally extending 100 flexible casing 14. The casings 13, 14 are of less length than the casings 10. The casings 13 and 14 are provided with stay members 15, 16 respectively, of less length than the length of said casings and which are positioned to terminate at a point a substantial 105

distance above the lower ends of the casings. The stay members 15, 16 are provided with coacting fastening means, as indicated at 17, for detachably connecting the sections 2 and 3 together.

Secured to the outer face of each of the sections 2, 3, at the bottom thereof, is a pair of resilient reinforcing pieces 18, 19. The piece 19 is positioned at the lower terminus 10 of a triangular shaped portion, and the piece 18 is arranged a substantial distance from the piece 19.

Secured to the pieces 18 and depending therefrom are adjustable hose supporters 20.

Secured to the lower end of the casing 13, as at 21, and to the reinforcing piece 19 of the section 2, as at 22, is a curved flexible coupling member or strap 23, which depends below the body 1 and couples the casing 13 20 with the bottom of the body 1. The upper end of the coupling member 23 is positioned at one side of the vertical median, at the center of the front of the body portion 1, and the lower end of the strap 23 is connected to the section 1 to one side of the connection 21.

Secured to the lower end of the casing 14, as at 24, and to the reinforcing piece 19 of the section 3, as at 25, is a curved flexible coupling member or strap 26, which depends below the body 1 and couples the casing 14 with the bottom of the body 1. The upper end of the coupling member 26 is positioned at one side of the vertical median, at the center of the front of the body 1, and the lower end of the strap 26 is connected to the section 1, to one side of the connection 24.

The coupling member 23 has slidably mounted thereon an automatically adjustable anchoring member 27 in the form of a hose supporter. The coupling member 26 has slidably mounted thereon an automatically adjustable anchoring member 28 in the form of a hose supporter.

The coupling members 23 and 26 extend in opposite directions with respect to each other, and provide means in connection with the elements 27 and 28 to cause a pair of direct downward pulls at the center of the front of the body portion and a pair of diagonal pulls in opposite directions from the triangular portions 8 and 9, across the front of the wearer, and such action prevents, when the garment is worn, the buckling or riding up of the body portion, irrespective of the attitude of the wearer, and further causes the snug fitting of the body portion against the hips and thighs of the wearer. As the anchoring elements 27 and 28 are slidably mounted on the coupling members 23 and 26, the said elements automatically adjust themselves to the several positions thereof with respect to the length of the coupling members so as to accommodate the various attitudes assumed by the wearer, and such accommodation is had without impart-

ing to the wearer any inconvenience or binding effect, and furthermore said coupling members 23 and 26 act in an equalizing manner so as to overcome any undue strain on the body portion or the hose thereby preventing the tearing of the latter. When the garment is worn the supporters 20 and anchoring elements 27 and 28 are connected or gripped to the hose of the wearer of the garment.

With reference to the modified form shown in Figure 2, the body portion, which is indicated generally by the reference character 29, is arcuate in contour and formed of an impervious elastic sheet 30 of pure rubber gum. The difference between the form shown in Figure 2 and that shown in Figure 1, is that the body portion of the garment illustrated in Figure 1 is formed of two sections detachably connected together, and whereas the body portion shown in Figure 2 is unitary. The body portion 29, centrally thereof, is provided with a flexible casing 31 and centrally of the lower part of the front thereof with a semi-heart shaped cut-away portion 32. The casing 31 extends from the top of the body portion 29 to the top edge of the cut-away portion 32, and is provided with stay members 33 which terminate a substantial distance above the top edge of said cut-away portion 32. The body portion 29 is formed with a pair of oppositely extending triangular shaped portions 34, 35, which extend towards each other. Elastic reinforcing pieces 36 and 37 are secured to the body portion 29 and arranged in the same manner as the reinforcing pieces 18 and 19, shown in Figure 1. Secured to and depending from the reinforcing pieces 36 are adjustable supporters 38. Curved coupling members 39 and 40 are connected to the body portion 29, and anchoring elements 41 and 42 are slidably mounted on the coupling members 39 and 40 respectively.

The coupling members 39 and 40 are set up with respect to the body portion 29 in the same manner as the coupling members 23 and 26 are set up with respect to the front of the body portion 1, and the anchoring elements 41 and 42 are similar in construction and arrangement with respect to the coupling members 39 and 40 as the anchoring elements 27, 28 with respect to the coupling members 23 and 26. The coupling members 39, 40, anchoring elements 41, 42, perform the same function as the coupling members 23, 26 and anchoring elements 27 and 28.

The lower terminus of each of the tapering portions 8, 9, 34 and 35 is positioned a substantial distance in a lateral direction from the vertical median, at the center of the front of the body portion of the garment, and as the lower ends of the coupling mem-

bers are arranged with respect to said vertical median in the same manner as the lower or free ends of the tapering portions, it is obvious that simultaneously with the 5 downward pulls acting centrally of the front of the body portion, diagonal pulls will be had on the body portion 1 in opposite directions, and further in a direction to intersect the plane of said vertical median, and each 10 coupling member and its associated anchoring element synchronously provide for a direct downward and a diagonal pull intersecting the direction of the downward pull, therefore, it is obvious that the body portion 15 cannot buckle or ride up, either at the center thereof or to each side of the center of the body portion. The coupling members, in connection with their associated anchoring elements, prevent any possibility of the lower 20 edge of the body portion curling upwardly. The diagonal pull in opposite directions causes the body portion to snugly fit the hips and thighs of the wearer and also prevents the curling of the lower termini of the 25 tapering portions.

It is thought that the many advantages of a garment, in accordance with this invention, can be readily understood, particularly that it provides for snug fitting and over- 30 comes buckling and riding up when worn, and although the preferred embodiment of the invention is as illustrated and described, yet changes in the details of construction can be had which will fall within the scope 35 of the invention as claimed.

What I claim is:—

1. A body garment comprising a body portion of band-like form to completely surround the body of the wearer and having the lower part of its front, centrally thereof, formed with a cut-out portion opening centrally of the bottom edge of said front, the top edge of said cut-out portion extended on each side of the vertical median of 40 said front and positioned above said bottom edge, the side edges of said cut-out portion extending towards each other at an inclination and each terminating at one side of said vertical median to provide in connection with said bottom edge a pair of oppositely disposed tapering portions extending towards each other, a pair of oppositely disposed curved depending strap-like coupling members having their upper ends fixedly 45 secured to said front at the top edge of said cut-out portion at each side of said vertical median, said members having their lower ends fixedly secured to said tapered portions in close proximity to the free ends thereof 50 and out of vertical alignment with said upper ends, and means slidably mounted on and automatically shiftable lengthwise of each of said coupling members for synchronously 55 exerting in connection with said tapered portions direct downward pulls and diagonal pulls in opposite direction on the garment with respect to the body of the wearer when the garment is worn, the upper end of each of said coupling members positioned 60 at one side of said vertical median.

diagonal pulls in opposite directions on the garment with respect to the body of the wearer when the garment is worn.

2. A body garment comprising a body portion of band-like form to completely surround the body of the wearer and having the lower part of its front, centrally thereof, formed with a cut-out portion opening centrally of the bottom edge of said front, the top edge of said cut-out portion extended on each side of the vertical median of said front and positioned above said bottom edge, the side edges of said cut-out portion extending towards each other at an inclination and each terminating at one side of said vertical median to provide in connection with said bottom edge a pair of oppositely disposed tapering portions extending towards each other, a reinforcement secured to the outer face of each tapered portion at 70 the free end thereof, a pair of oppositely disposed curved depending strap-like coupling members having their upper ends fixedly secured to said front at the top edge of said cut-out portion and their lower ends 75 fixedly secured to said reinforcements and out of vertical alignment with said upper ends, and means slidably mounted on and automatically shiftable lengthwise of each 80 of said coupling members for synchronously exerting in connection with said tapered portions direct downward pulls and diagonal pulls in opposite direction on the garment with respect to the body of the wearer when the garment is worn, the upper end of each of said coupling members positioned 85 at one side of said vertical median.

3. A body garment comprising an elastic body portion of band-like form to completely surround the body of the wearer and having the lower part of its front centrally thereof, formed with a cutout portion opening centrally of the bottom edge of said front, the top edge of said cutout portion extending a substantial distance from and on each side of the vertical median of said front and positioned a substantial distance above the bottom edge of said body portion, the side edges of said cutout portions extending towards each other at an inclination 105 and each terminating at one side of said vertical median to provide in connection with said bottom edge a pair of oppositely disposed tapering portions extending towards each other, a reinforcement secured to the outer face of each of said tapered portions at the free end thereof, a pair of oppositely disposed, curved, depending strap-like coupling members having their upper ends spaced from each other and fixedly secured to said front at the top edge of said cutout portions, said members having their lower ends fixedly secured to said reinforcements, and lengthwise adjustable means 110 slidably mounted on and automatically 115 shiftable lengthwise of each of said coupling members for synchronously exerting in connection with said tapered portions direct downward pulls and diagonal pulls in opposite direction on the garment with respect to the body of the wearer when the garment is worn, the upper end of each of said coupling members positioned 120 at one side of said vertical median.

shiftable lengthwise of each of said coupling members for synchronously exerting in connection with said tapered portions direct downward pulls and diagonal pulls in opposite directions on the garment with respect to the body of the wearer when the garment is worn, the upper end of each of

said coupling members positioned at one side of and spaced from said vertical median. 10

In testimony whereof, I affix my signature hereto.

RALPH S. THOMPSON.
